UNITED STATES PATENT OFFICE.

DAVID RUSH McCULLOUGH, OF OAKLAND, CALIFORNIA.

DESIGN FOR A COMBINED WATCH AND KEY-RING STRAP.

59,025.

Specification for Design.

Patented Sept. 13, 1921.

Application filed March 2, 1921. Serial No. 449,227. Term of patent 3½ years.

To all whom it may concern:

Be it known that I, DAVID RUSH McCULLOUGH, a citizen of the United States, residing in Oakland, in the county of Alameda and State of California, have invented a new, original, and ornamental Design for a Combined Watch and Key-Ring Strap, of which the following is a specification, reference being had to the accompanying drawing, forming part thereof.

The figure is a perspective view of a combined watch and key ring strap, showing my new design.

I claim:

The ornamental design for a combined watch and key ring strap, substantially as shown.

DAVID RUSH McCULLOUGH.
